UNITED STATES PATENT OFFICE

HARRY R. PRIEST, OF LOUDONVILLE, OHIO

SUCTION-CUP FOR ARTIFICIAL TEETH

Application filed May 31, 1930. Serial No. 458,654.

This invention relates to artificial teeth and more particularly to suction cups for preventing loosening of the same, of that general type described in my former Patent No. 912,977, dated February 16, 1909.

An object of the present invention is to provide a novel suction cup in which the rivet or button which secures the suction cup to the plate will be prevented from touching the tissues of the mouth.

A still further object is to provide a suction cup in which the button will be formed with a relatively short neck and the rubber cup will be so formed as to present an annular rim 15 within which the head of the button is countersunk when the cup is under compression, these two features of construction permitting of a relatively thin denture or plate being employed and at the same time positively preventing the head of the button from contact with the mouth.

With the above and other objects in view the invention consists in certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification:

Figure 1 is a perspective view showing the upper denture or plate equipped with my improved suction cup,

Fig. 2 is a cross sectional view through the cup and plate greatly enlarged and showing the cup in normal position,

Fig. 3 is a cross sectional view similar to Fig. 2 but showing the cup under compression, and

Fig. 4 is a detail plan view of the cup.

Referring now to the drawing in which like characters of reference designate similar parts in the various views, 10 designates an artificial denture or plate, that for an upper set of artificial teeth being illustrated, although it is to be understood that my invention is equally applicable to lower plates.

The plate 10 is formed with a recess 11 for

the reception of the button and suction cup, and the button in the present embodiment is composed of a single piece of aluminum or similar light and ductile metal which is so stamped and shaped as to produce an annular base 12 designed to be embedded and vulcanized in the plate. The base is formed with a plurality of openings 13 through which the material of the plate passes in order to securely hold the button to the plate. 55 The button is also formed with an integral hollow neck 14 and a disk head 15. The material of the plate passes into the neck and extends to the underneath face of the head and assists in rigidly securing the button to 60 the plate.

The suction cup 16 is preferably formed of soft strong resilient rubber and is molded with a center opening 17 which is stretched over the neck 14 and secures the cup to the button, and is also molded with an upstanding annular portion or rim 18 which extends beyond the head of the button when the suction cup is under compression as shown in Fig. 3 and when the cup is not under compression, as shown in Fig. 2. This rim 18 extends beyond the plane of the head of the button so that the button head is virtually counter-sunk in the rim and consequently when the rim contacts with the tissues of the mouth no part of the head can touch and injure the tissues. The skirt or that portion of the suction cup disposed outside of the annular rim, as best shown in Fig. 3, is substantially flattened and lies at an angle to the annular portion or rim 18. The skirt is receivable in the above mentioned recess 11 and forms a firm anchorage for the plate in the mouth.

In practice it has been found that by constructing the button with a relatively short neck, as shown in Figs. 2 and 3, the suction cup and button positively prevent loosening of the plate in the mouth without requiring the use of the usual thick plate, and consequently the plate itself may be much thinner and lighter than hitherto. The extreme thinness and lightness of the plate in use has been found to improve the quality of speech 100

of the wearer in contrast to the use of thick plates which distort the voice.

My invention may be characterized by the use of a rivet or button with a short neck over which the center perforation of the suction cup is stretched, while the cup itself is so formed that the material of the cup extends beyond the plane of the head of the button in an annular rim which engages the tissues of the mouth leaving the head counter-sunk in said rim.

Having thus described the invention, I claim:

A securing device for artificial denture or plates comprising a button having a base adapted to be embedded in the material of the plate and having a short neck and a head, and a rubber suction cup molded with a center opening receiving said neck and with an upstanding annular portion beyond said head when the cup is compressed and when the cup is not compressed, the outer portion of the cup being substantially flattened and lying at an angle to the annular portion.

In testimony whereof I affix my signature.

HARRY R. PRIEST. [L. S.]
